RAIL JOINT CONNECTION

Max Rüping, Frankfort-on-the-Main,
GermanyApplication July 28, 1937, Serial No. 156,051
In Germany August 8, 1936

6 Claims. (Cl. 238—168)

My invention relates to improvements in rail joint connections, in which the two abutting rail ends are arranged on a bridge plate resting on two adjacent sleepers.

The objects of my invention are: first, to provide a rail connection having three supporting points for the abutting rail ends, said supporting points being rigidly braced with respect to each other; second, to afford facilities for the proper adjustment of one of the supports to bring the three supporting points to one and the same elevation regardless of the irregularities of the track; and third, to produce a rail connection with a three-point support which may be readily readjusted during use, if necessary, without dismounting the joint.

I attain these objects by means of a construction, one embodiment of which is illustratively exemplified in the accompanying drawing, in which:

Fig. 1 is a side elevational view of the new rail connection with a part of the bridge plate broken away and some elements of the construction shown in section;

Fig. 2 is an elevational plan view of the joint from above with the rails and the shim plate omitted, and

Fig. 3 is a substantially transverse sectional view taken on line 3—3 of Fig. 1.

Referring to the drawing, 11 denotes a bridge plate, which rests at its ends 12 upon two sleepers 13, and which is provided with two upstanding longitudinal ribs 14 forming the seat for the rail flanges 15. Two longitudinal parallel slits 16 are provided in the bridge plate 11 inside and adjacent the ribs 14, the slits dividing the suspended part of the bridge plate 11 into three portions, viz., two side bars 17, forming a rigid frame with the solid ends 12 of the bridge plate 11 (see Fig. 2), and a longitudinal mid-portion 18 curved downwardly to form a depending cradle-like carrier which is integral with said rigid frame (see Fig. 1).

The two rails 19 are supported upon the solid ends 12 of the bridge plate 11 and the sleepers 13, respectively, and project towards each other until their ends abut above the center of the cradle carrier 18. The rails 19 are fixed to the sleepers 13 by means of elastic rail spikes 21 projecting through holes 22 in the bridge plate 11. Fish plates 23 connect the rail ends 20 to each other in the usual manner.

Disposed in the space between the cradle 18 and the rail ends 20 is an assembly of elements composed as follows: A wedge 24 is arranged adjustably in transverse direction between two

correspondingly tapered suitably recessed expansion plates 25 and 26. The lower expansion plate 25 is provided with longitudinal downwardly projecting shoulders 27 which straddle the cradle 18. The upper expansion plate 26 fits between the ribs 14 of the bridge plate 11 and is held by the same against transverse displacement. A rubber pad 28 is disposed on the upper expansion plate 26 and is covered by a wood shim plate 29 having a width substantially equal to that of the rail flanges 15 and a length corresponding to that of the bridge plate 11. The rail flanges 15 rest immediately upon the shim plate 29.

The correct adjustment of the supporting members is effected by driving the wedge 24 firmly between the two expansion plates 25 and 26 until the upper surface of the rubber pad 28 is on the same elevation as the surfaces of the solid ends 12 of the bridge plate 11.

The outer end of the wedge 24 is provided with a plurality of transversely aligned holes 30, which correspond to a plurality of similarly arranged but differently spaced holes 31 in one side bar 17 of the bridge plate 11. A pin 32 is inserted through one of the holes 31 in the bridge plate 11 into one of the holes 30 of the wedge 24 to secure the latter in the desired position against movement.

After proper adjustment of the wedge 24, the rail ends 20 immediately adjacent the joint are firmly supported at an elevation equal to that of the other supporting points on the sleepers 13 and all parts of the joint connection are rigidly braced with respect to each other. The firm support of the rail ends at three points and the taut arrangement of all elements of the joint connection cause a considerable reduction in hammering or impacts of the wheels against the joint. These impacts are still further reduced and absorbed by the elastic rubber pad 28 disposed directly beneath the rail flanges. The shim plate 29 protects the rubber pad 28 against frictional disintegration due to temperature changes resulting in the expansion and contraction of the rail.

Any loosening of the expansion plates 25, 26, due to wear and tear of the parts, may be easily taken up. For this purpose the pin 32 is withdrawn and the wedge 24 is driven further between the expansion plates 25 and 26 to spread the same until the desired position is attained, whereupon the pin 32 is inserted again in the respective holes 30 and 31.

I claim:

1. A rail joint connection comprising two sleep-

ers, a bridge plate resting at its ends upon said sleepers, said bridge plate comprising a rigid straight frame and having a longitudinal mid-portion integral with the solid ends and side bars separated from said mid-portion said mid-portion being curved downwardly to form a cradle-like carrier, two abutting rails supported on and secured to said bridge plate ends, respectively, fish plates connecting said abutting rails, and an expansion assembly inserted between the cradle-like carrier and the flanges of the adjacent rail ends, said expansion assembly including a transversely adjustable wedge and an upper expansion plate contacting said adjustable wedge with a correspondingly tapered lower surface and being secured against transverse displacements between the straight side bars of said frame.

2. A rail joint connection, as claimed in claim 1, in which said expansion assembly comprises further a lower expansion plate contacting said transversely adjustable wedge with a correspondingly tapered upper surface, and means to engage said lower expansion plate with said cradle-like carrier so as to secure said plate against transverse displacements.

3. A rail joint connection, as claimed in claim 1, in which the outer portion of said wedge is provided with a plurality of transversely aligned

holes and in which a plurality of differently spaced holes is arranged along the same transverse line in the corresponding side bar of the bridge plate, comprising further a pin adapted to be inserted into any two holes having been brought into registry, whereby said wedge is secured against movement.

4. A rail joint connection, as claimed in claim 1, in which said expansion assembly comprises further a resilient pad disposed on said upper expansion plate between said side bars.

5. A rail joint connection, as claimed in claim 1, in which said expansion assembly comprises further a rubber pad disposed over said upper expansion plate, and a wood shim plate arranged between said rubber pad and the rail flanges, said wood shim plate having a width equal to that of the rail flange and a length corresponding to that of the bridge plate, said rubber pad and shim plate being secured against transverse displacements between the side bars of said frame.

6. A rail joint connection, as claimed in claim 1, in which two parallel longitudinal ribs are provided on said frame adjacent the inner edges of said side bars to accommodate the flanges of said abutting rails.

MAX RÜPING.
